UNITED STATES PATENT OFFICE.

CHARLES O. MOOK, OF JACKSON, MICHIGAN.

DUST-COLLECTOR FOR MILLS.

SPECIFICATION forming part of Letters Patent No. 309,078, dated December 9, 1884.

Application filed June 20, 1884. (No model.)

To all whom it may concern:

Be it known that I, CHARLES O. MOOK, a citizen of the United States, residing at Jackson, in the county of Jackson and State of Michigan, have invented certain new and useful Improvements in Dust-Collectors for Mills; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to that class of dust-collectors for flouring and other mills in which the dust-laden air is conducted from the separate machines or apartments of the mill to a dust-collecting chamber, where the air is sifted 20 or freed from dust and permitted to escape.

25 My invention is applicable to all classes of mills where it is desired to arrest or collect the dust arising therein, and its nature and objects will be fully disclosed in the following description and the novel features and combinations subsequently defined in the claims at the close thereof.

In the accompanying drawings, Figure 1 is a vertical section of a dust-collecting chamber 30 embodying my improvements. Fig. 2 is a horizontal section thereof on line $x-x$, Fig. 1. Fig. 3 is a vertical section of such a dust-collecting chamber embodying my features not shown in Fig. 1. Fig. 4 is a longitudinal section taken on line $y-y$ of Fig. 3. Fig. 5 illustrates in elevation and section a detail of the blast-regulating device.

In the several views the same reference-letters are used to indicate corresponding parts.

40 The casing A is a rigid structure, which may be located in any convenient place—as, for instance, it may form a cupola at the top of a mill, or be an independent structure located adjacent to a mill.

45 Arranged centrally at the top of the casing A, and forming a part thereof, is a ventilating-chamber, A', the side walls of which are provided with ventilators a' , (shown in Figs. 1 and 3,) and across each of these ventilators is 50 stretched a piece of reticulated cloth, a^3 , such

as is commonly used in devices of this character.

Interposed between the ventilating-chamber A' and the main or dust chamber a of the collector is a hinged frame, B, also clothed with 55 reticulated cloth b , and held normally in a horizontal position by a bolt, b' , or other equivalent means. The walls of the casing A are provided with ventilators a^2 , similar to but proportionately smaller than the ventilators 60 a' described in connection with the ventilating-chamber A', and these ventilators a^2 are also clothed with reticulated cloth a^4 . Valves or gates C are secured in proximity to these ventilators a^2 , and adapted to be moved over 65 or away from the ventilators, to either prevent or permit of the passage of air-currents through them. I have in the drawings illustrated said gates as mounted to slide in ways or guides c ; but it will be understood that the same object 70 would be accomplished if they were secured by hinges at one edge or by a pivot-bolt, it only being essential that they be adapted to be so moved as to cover or uncover the ventilating-openings, so that air may escape through 75 them or not, as circumstances may require.

At a suitable distance below the top of the dust-chamber a are discharge-openings D, or "nozzles," as I shall call them, formed by inclined boards d , arranged in pairs, as shown; 80 and to the inclined sides d of these nozzles are adjustably secured slide-boards D', adapted to be moved upward to project beyond the mouth of the nozzle and decrease the width of the opening thereof.

85 As illustrated in the drawings, the inclined sides d of the nozzles are provided with upwardly-projecting screw-bolts d^2 , which pass through transverse slots d^1 in the slide-boards, and serve as guides for said boards, the slide-boards being adjusted by hand and secured against movement after adjustment by means of thumb-nuts d^3 , fitted upon the bolts d^2 ; but it will be understood that I do not wish to limit myself to this specific construction, as it is evident that the slide-boards may be adjusted and held by any of the many well-known mechanical devices used for similar purposes.

The floor E of the dust-chamber may be made hopper-shaped, as indicated in Fig. 1, 100

horizontal, as shown in Fig. 2, or a series of conveyers of any of the well-known forms may be arranged below the level of the nozzles, to receive the dust as it falls and conduct it to any 5 desired receptacle.

The operation of my dust-collector is as follows: The mill to which said collector is to be applied is provided at suitable points with the usual apparatus—such as exhaust fans and 10 pipes F—to collect the dust or refuse and conduct it to a common receptacle. In using my dust-collector these pipes F discharge the dust-laden air-current upward through the nozzles D into the dust-chamber a, where, as the current 15 is less confined, a greater part of the dust will escape from the upward current and fall below the nozzles. The lighter particles of dust will, however, be carried upward until arrested by the reticulated cloth b of the hinged 20 frame B. Where the air-current is too strong this fine dust will be pressed against the cloth of the frame B until, eventually, the accumulation of fine dust upon the cloth will be so great as to prevent the passage of air. To overcome 25 this objection I have provided the sides of the dust-chamber with cloth-covered ventilators a², through which a portion of the air-current can pass, one or more of the gates C having been first properly adjusted.

30 I have found that a portion of the very fine particles of dust will pass through the cloth on frame B into the ventilating-chamber, and to prevent the escape of this dust into the open air I have clothed the ventilators a² with reticulated cloth, as shown. As there is a free circulation of air from the exterior of the building through this ventilating-chamber, the fine dust will not be apt to lodge upon the cloths a² in sufficient quantities to prevent the escape 35 of air from the dust-chamber. This ventilating-chamber may be cleared of dust from time to time, as necessity requires, by withdrawing the bolt b', which sustains the hinged frame B, and permitting the frame to swing down on 40 its hinges and the dust to fall into the dust-chamber, it being necessary, of course, during this operation to stop the fans in the mill, so that there will be no air-current to carry the dust against the cloths.

45 In Fig. 3 I have illustrated a modification of my dust-collector, devised with special reference to the requirements of wood-working factories.

G G are screens of wire-cloth, arranged 50 across the nozzles D below their discharge-openings, to prevent shavings and the like from being carried up into the dust-room. I prefer to mount below these screens horizontal shafts H, carrying one or more radial arms, 55 H', provided at their outer ends with brushes h', which upon the revolution of the shafts sweep the under sides of the screens G and remove such particles as are too large to pass through the screens; but these shafts and 60 brushes may be dispensed with. To avoid 65 danger from fire, the bearings h, in which these

shafts H are journaled, are mounted at the exterior of the casing A, as are also the pulleys or gear-wheels which connect the shafts with the source of power. I have shown 70 these bearings and pulleys exposed to the atmosphere; but it will be understood that in practice they will be protected by suitable 75 housings. The portion of the interior of the casing A below the screens G forms a shavings-room, J, which communicates by means of a sliding door, i, with one side of a fuel-room, I, at the other side of which is a similar sliding door, i', to afford communication with the furnace-room, or with a duct leading 80 to said furnace-room. Upon closing the door i' and opening the door i the blast from the pipes F will carry shavings into the fuel-room I, and upon closing said door i and opening the door i' the shavings may be 85 taken from the room I as required.

It will be observed that while a dust-collector embodying these modifications is especially adapted for use in connection with wood-working factories, they would in no wise detract from its usefulness as a flour-duster.

Having thus described my invention, what I claim as new, and desire to secure by Letters Patent, is—

1. A dust-collector for mills, consisting, substantially as before set forth, of a dust-chamber, nozzles adapted to discharge upwardly into said chamber, a ventilating-chamber surmounting the dust-chamber and having cloth-covered ventilating-openings, and a hinged cloth-covered frame interposed between the dust and ventilating chambers.

2. The combination, substantially as before set forth, of the dust-chamber, the described ventilating-chamber surmounting said dust-chamber, the hinged cloth-covered frame interposed between the dust and ventilating chambers, the nozzles adapted to discharge upwardly into the dust-chamber, and the adjustable slide-boards mounted upon the inclined sides of the nozzles.

3. The combination, substantially as before set forth, of the dust-chamber, the described ventilating-chamber, the hinged cloth-covered frame interposed between the dust and ventilating chambers, the nozzles adapted to discharge upwardly into the dust-chamber, and means, substantially such as described, for conducting the dust from the dust-chamber.

4. A dust-collector embodying the following parts in combination: a dust-chamber provided with an opening or openings for the passage of air, a pipe or conduit leading from the air-forcing apparatus of a mill to the interior of the dust-chamber, reticulated cloth interposed between the discharge end of said pipe or conduit and the exit-openings of the dust-chamber, and wire screen secured near the discharge end of the pipe or conduit.

5. The combination, substantially as before set forth, of the dust-chamber provided with independent cloth-covered openings, the ad-

justable gate or gates for closing one or more of said openings, the nozzles adapted to discharge upwardly into the dust-chamber, and the wire screens secured across said nozzles 5 near their discharge-openings.

6. The combination, with the dust-chamber, the nozzles, and the screens, arranged as described, of the brushes secured below the screens, and adapted to sweep the under surface thereof.

7. The combination, with the dust-chamber, the nozzles, and the screens, all arranged as described, of the horizontal shafts, the brushes mounted thereon, and mechanical de-

vices to connect the shaft with the source of power.

8. The combination, with the dust-chamber, the nozzles, the screens, and the rotating brushes, of the shavings-room and the fuel-room, provided at opposite sides with sliding doors, substantially as and for the purpose specified.

In testimony whereof I affix my signature in presence of two witnesses.

CHARLES O. MOOK.
